UNITED STATES PATENT OFFICE

2,437,654

FOUNDATION GARMENT

Irving Rosner, New York, N. Y., assignor to Even-Pul Foundations, Inc., New York, N. Y., a corporation of New York

Application February 27, 1945, Serial No. 579,956

1 Claim. (Cl. 2—30)

1

This invention relates to an improved foundation garment of the type shown in my U. S. Letters Patent No. 2,272,023, dated February 3, 1942.

The primary object of the present invention is to provide a foundation garment of the above kind, adapted for effectively supporting the breasts, reducing the abdomen and keeping the waist in proper form without discomfort to the wearer.

A further object of the invention is to provide a garment of the above kind in which maximum freedom of movement is provided for between the brassière section and the girdle section of the garment.

Another object of the invention is to provide a foundation garment which gives maximum freedom to the wearer and is most efficient in providing the desired support and form-keeping qualities.

The present invention consists in the novel form, combination and arrangement of parts hereinafter more fully described, shown in the accompanying drawings and claim.

In the drawings, wherein like reference characters indicate corresponding parts throughout the several views:

Figure 1 is a front elevational view of a foundation garment constructed in accordance with the present invention.

Figure 2 is a rear elevational view thereof.

Figure 3 is a horizontal section taken on line 3—3 of Figure 1.

Figure 4 is an enlarged fragmentary vertical section taken on line 4—4 of Figure 2.

Referring in detail to the drawings, the present garment includes a lower girdle section A and an upper brassière section B that constitutes a complete brassière and is telescoped at its lower portion over the upper portion of the girdle section A. Brassière section B is permanently attached at its sides to the sides of the girdle section A, as at 5, and, except for certain flexible and preferably elastic connections to be presently described, is completely free from said girdle section at the front and back of the garment. The elastic connections mentioned consist of a central connection 6 and side connections 7 between the lower edge of the brassière section B and the girdle section A at the back of the garment, and a central connection 8 between the lower edge of the brassière section B and the girdle section A at the front of the garment. The elastic connections 6 and 7 are permanent, but a hook-and-eye connection is provided at 9 between the elastic connection 8 and the girdle

section A so as to permit the section 8 to be used or to be rendered inoperative according to the desires of the wearer. In some cases, a downward elastic pull is desired on the brassière section B at the front, in which case the hook-and-eye connection 9 will be used to render the connection 8 operative. It will be apparent, however, that the elastic connections 6, 7 and 8 permit ready yielding of the brassière section B upwardly relative to the girdle section A at both the back and front of the garment.

As shown, the girdle section A has a front portion composed of a central panel 10 and side panels 11 which are inelastic, and elastic inserts 12 between the panels 10 and 11. It further includes a back portion composed of a central inelastic panel 13 and elastic inserts between the panel 13 and inelastic side panels 15. At the front, the girdle section A is provided in its lower edge with an elastic gusset 16 that is provided specifically in the central panel 10.

The brassière section B has a front portion composed of inelastic central and side panels 17 and 18 with elastic inserts 19 therebetween. It further includes a back portion composed of inelastic central and side panels 20 and 21. The panel 20 has a central elastic gusset in the upper edge thereof, as at 22, while the panels 21 have elastic gussets 23 in the lower edges thereof. The usual breast pockets 24 are provided in the front upper portion of the brassière section, and the latter has the usual shoulder straps 25.

A belt C is located on the inner face of the front portion of the girdle section A substantially as described in my above-mentioned U. S. Letters Patent, and the same need not be described in detail herein. The usual hose supporters 26 and 27 are also provided on the lower edge of the girdle section A.

It will be seen that the back of the girdle need not be extended upwardly to form the back of the brassière section. Also, the complete brassière section encircles the entire upper portion of the girdle section, but is entirely free from the latter except at the sides and except for the elastic connections 6, 7 and 8. This provides for freedom of movement and allows the brassière to yield upwardly entirely across the back and front of the garment relative to the girdle section. By permanently connecting the sections at 5, they are properly held in assembled relation at all times, and when a downward pull is not desired on the brassière section at the front of the garment, the hook-and-eye connection 9 may be disengaged so as to render the elastic connection 8 inoperative.

From the foregoing description, it is believed that the construction and advantages of the present invention will be readily understood and appreciated by those skilled in the art. Minor changes may be made in details of construction such as fairly fall within the spirit and scope of the invention as claimed. If desired, the garment may be partially or wholly divided vertically and equipped with means to connect the vertical edges so as to facilitate donning of the garment, as commonly practised in the construction of corsets.

What I claim is:

A foundation garment comprising horizontally yieldable complete brassière and girdle sections, the brassière section having a back portion composed of inelastic central and side panels respectively having central V-shaped elastic gussets in the upper and lower edges thereof, the lower portion of said brassière section being telescoped over the upper portion of said girdle section, permanent connections between the sides of the overlapped portions of said sections, elastic straps permanently attached at their upper ends to the lower edge of the back portion of said brassière section respectively centrally between and adjacent the sides of said back portion and permanently connected at their lower ends to the outer face of the back portion of the girdle section at points spaced from and below the lower edge of the brassière section to yieldingly resist 30

relative separating movement of the back portions of said sections, a single further elastic strap permanently attached at its upper end to the lower edge of the front portion of said brassière section centrally between the sides of said front portion, and means to detachably connect the lower end of the last named strap to the outer face of the front portion of the girdle section at a point spaced from and below the lower edge of the brassière section to yieldingly resist relative separating movement of the front portions of said sections, said permanent side connections and straps being the only connections between said sections.

IRVING ROSNER.
